FIG. 1

FIG. 2

FIG. 4

FIG. 3

FIG. 1 is a perspective view of a cigarette lighter showing my new design;

FIG. 2 is an end elevation thereof;

FIG. 3 is a top plan view thereof; and

FIG. 4 is a perspective view thereof with the lever handle shown in operative position.

The characteristic features of my design reside in the configuration and arrangement of the flame adjusting wheel, flame port and pressure adjusting lever in combination with the top of the lighter as shown.

The undisclosed side is identical to the side shown and the bottom is plain.

I claim:

The ornamental design for a cigarette lighter, as shown and described.
